NONREFILLABLE CLOSURE FOR BOTTLES
AND OTHER CONTAINERS

Gilbert Jackson, New York, N. Y.

Application September 4, 1934, Serial No. 742,696

6 Claims. (Cl. 215—28)

My invention relates to closures and it particularly relates to non-refillable closures for bottles and similar liquid containing receptacles.

In my Patent No. 1,348,116, dated July 27, 1920 and in my copending application Serial No. 697,892, filed November 1, 1933, I have disclosed non-refillable bottle closures or caps which have for their objects the prevention of the refilling of bottles after they had been emptied.

10. In said patent there was disclosed a hollow valve member which cooperated with a cylindrical valve seat inserted in the mouth of the bottle. Above the valve and the valve seat was positioned a movable ball. The ball was confined between the valve member on one side, and at the other side contacted with a concave contact member.

As disclosed in said patent, the valve member was preferably of a porous material. This porous material was of such a nature that the valve, when wet, would attach itself firmly to its seat when the bottle was upright and yet not prevent said valve leaving its seat, when the bottle was inverted.

25. In said copending application there was disclosed a non-refillable bottle closure similarly provided with a movable ball, but in which the movable ball was thrown into locking position by means of a conical support member when the bottle was placed upright so that it was not possible to place any liquid in the bottle through the closure when the bottle was in this position. However, the closure of this copending application was preferably of molded material, such as 30 bakelite, and for some purposes it was found that bakelite materials were not altogether satisfactory, as they tended to give a taste and/or odor to certain types of liquids which might be contained in the bottle or container.

40. Further difficulties were experienced inasmuch as the locking ball members often would wedge in locking the valve of the closure, and in such case it was necessary to shake or knock the bottle to move the ball to open position when the bottle was inverted, which was undesirable.

An object of the present invention is to provide a non-refillable bottle closure of the type, as above described, in which the valve member and its associated parts would be constructed of material, which will not give rise to any odor or taste in the liquid in the container or bottle, and in which the various parts of the structure may be most inexpensively and easily constructed from readily available materials, as for example, ceramic materials.

Another object is to provide a non-refillable bottle closure of the type above described in which the closure is positively effected and the valve is forced positively to its seat when the bottle is not in inverted discharging position.

5. Another object is to provide a bottle closure of the ball locking type, such as above described, in which the ball will not be wedged when locking the closure in non-refillable condition, and in which the ball will most readily move from locking to un-locking position, depending upon the position of the container from which the liquid is to be dispensed.

Other objects will appear during the course of the following specification.

15. In accomplishing the objects of the present invention it has been found most suitable in one embodiment to provide a valve casing having an upper closure, exteriorly exposed, and a lower opening to communicate with the interior of the 20 container or bottle. The lower portion of the valve casing may be of a decreased diameter so as to fit conveniently into the neck of the bottle, a shoulder being preferably provided on the casing to limit insertion thereof.

25. Internally positioned in the valve casing is a valve member preferably of hollow construction, the lower end of which valve member is conformed so as to cooperate with a valve seat interiorly formed in the bottom of the casing adjacent the 30 interior opening thereof above described. In the upper part of said casing is preferably provided a ball which cooperates with a concaved member in the upper part of the casing and with a conical or other domed portion at the top of the movable 35 valve.

35. In producing the closure of the present invention from ceramic materials, it has been found most desirable to form the outer casing in two sections; a lower casing having a reduced diameter with satisfactory clearance to fit into a neck of the bottle; and the upper casing at its lower end being interiorly shouldered and exteriorly flanged; the interior shoulder being for reception of the lower external casing member and the external flange being designed for cooperation with a corresponding flange at the top of the bottle; and an aluminum ferrule together with an immediate cork gasket enabling a most satisfactory and permanent liquid tight connection between 45 the closure and the bottle.

40. The lower external casing member is preferably designed to receive a hollow ceramic valve member which has a curved seat to fit a correspondingly formed seat in the lower casing mem- 55

ber, while the upper external casing member is preferably designed to receive the locking ball and preferably contains said concave member which permits the ball to fall away from the valve when the bottle is in inverted pouring position.

The conical or domed portion at the top of the movable valve is preferably formed so that on all sides of the central peak it will have a curved contour which will approximate the curvature of the ball.

In the accompanying drawing in which are shown one or more of various possible embodiments of the several features of the invention,

Fig. 1 is a longitudinal cross sectional view of the non-refillable sealing device of my invention.

Fig. 2 is transverse sectional view upon the line 2—2 of Fig. 1.

Fig. 3 is a transverse sectional view upon the line 3—3 of Fig. 1.

Fig. 4 is a top view of the conical portion at the top of the movable valve for controlling the position of the ball.

Fig. 4a is a view similar to Fig. 4 of a modification, and

Fig. 5 is a top perspective view of the hollow valve member with its cover portion removed.

Referring to Fig. 1, the bottle or other container B is provided with a cylindrical mouth 10. The bottle is adapted to receive alcoholic beverages or any other liquid to be dispensed. The upper cylindrical valve casing member 12 is provided with a lower insert portion 13 of reduced diameter, which is inserted in the opening 10 in the mouth or neck of the bottle B, preferably with a slight clearance. The lower insert portion is provided with a flange 8 at its upper end, which fits into the shoulder 9 on the interior of the upper casing section 12, the upper section 12 and the lower section 13 being held together by means of the sealing wax 7, which is preferably of a material not affected by alcoholic beverages or other liquids which may be contained in the bottle B.

It is noted that the shoulder 9 is enlarged at 6 to receive the sealing wax body 7. The upper casing 12 is also provided with an exterior flange 14 which cooperates with a corresponding projection 15 on the bottle, the flange 14 and the flange 15 being held together by the aluminum ferrule 16, said aluminum ferrule compressing the cork gasket 52 between the flanges 14 and 15 to form a liquid-tight connection.

The casing 13 is provided with a lower opening 17, the upper part of which is provided with the spherical depression 19 above the groove 18, said depression 19 serving as a valve seat to cooperate with the spherical surface 20 on the valve member 21. The valve member 21, as shown in Figs. 1 and 5 consists of a cylindrical hollow cup-shaped body 22, exteriorly provided with symmetrically spaced fins 23 (see also Fig. 3). The fins 23 centrally locate the valve within the lower chamber 24 of the lower casing member 13.

The lower part of the valve member 21, as indicated at 25, projects downwardly past the conical valve seat 19 into the opening 17 and is slightly flattened, as indicated at 26, during the course of manufacture (see Fig. 1). The lower portions of the fins are cut off substantially above the bottom 26, as indicated at 27 (see Figs. 1 and 5), so that they will clear the valve seat 19.

As shown in Fig. 3, the fins 23 space the cylindrical body 22 from the walls of the lower chamber 24 of the casing 12 with the formation of the flow passages 28, which permit ready egress of liquid from the mouth 10 of the bottle B past the

valve body 21, when the valve is lifted from its seat 19.

The upper portions of the fins of the valve body 22, are also cut off below the top of the valve body 22, as shown at 29 in Figs. 1 and 5. Into the upper portion of the cup 22 is inserted the lower contact element 30 for the locking ball 31. The contact element 30 contacts at its lower top with the top face of the valve member 21 and is preferably ceramically united therewith. The sides of 10 the disk member 30 extend beyond the body 22.

When the contact member 30 is ceramically united with the body 22, a body of air will be confined in the interior of the cup 34 giving it buoyancy. The upper part of the ball contact 15 member 30 is suitably shaped to cause the ball 31, as shown in Fig. 1, to roll outwardly of the casing 12 against the interior wall of the middle or intermediate chamber 35 when the bottle is upright.

In the present invention a curved conical surface 36 is shown, but it is understood that other similar types of surfaces may be employed for causing the ball to roll toward the wall of the middle chamber 35 of the casing 12.

As shown in Figs. 1 and 2 in the upper chamber 25 31 of the casing 12 is positioned the concave ball contact member 38 with the radial ribs 45, which contact member is preferably ceramically united with the symmetrically positioned angular fins 39 of the casing 12.

The concavity or depression 40 of the element 38, as shown in Fig. 1, is adapted to receive the ball 31 when the casing 12 is inverted with the bottle 10. When the bottle is in normal upright position, as shown in Fig. 1, the ball 31 will be 35 diverted to the outside of the chamber 35 by the cone 36 so that the ball 31 will fall or roll along the slope of the upper contact member of the cone 36 of the lower contact member 30, as indicated in Fig. 1, to below the lower edge 41. 40

As indicated in Fig. 2, the fins 39 will form the flow passages 42, symmetrically positioned around the periphery of the chamber 31. These flow passages 42 will cooperate with the flow passages 28 of Fig. 3 to permit liquid to flow past the valve 45 21 and the concave contact member 38.

The casing element 12 is provided with a center opening 50 which cooperates with the passages 42 past the concave contact member 38 and the passage 28 past the valve member 21 and with the opening 17 in the lower part of the casing 12, whereby liquid may be poured out of the inverted bottle 10, when the valve 21 is lifted from its seat 19.

In operation, when the bottle is in upright position or is in horizontal position, the ball 31 will slide or roll over the cone 36 to the side of the chamber 35, contacting with the interior walls thereof, as indicated at Fig. 1. When the ball 31 moves to the side of the chamber 35, it will 55 position itself between the outer lower portion 41 of the upper concave contact member 38 and the lower domed contact member 30 and will force the valve 22 against its seat 19, preventing flow of liquid reversely from the opening 50 and 60 through the opening 17 into the bottle 10, so that the bottle cannot be refilled.

When the bottle has been turned so that its mouth is inclined downwardly with an inclination substantially below horizontal, approaching 70 the vertical inverted position, the ball 31 will roll or slide into the concavity 40. This will permit the valve 22 to move from its seat 19 under the pressure of liquid in the bottle 10, whereby a ready exit of liquor may take place through the 75

opening 17, the passages 28 and 42 and the opening 50.

The upper face of the lower ball contact member 30 may also be domed to conform with the concavity of the depression 40. In any case, at the axis of the combination at 51, there would be a vertical spacing between the uppermost portion of the dome 36 and the uppermost portion of the dome 40 which will be greater than the maximum diameter of the ball. Toward the walls of the chamber 35 this spacing should decrease so that the ball will have substantially no clearance as it moves under the influence of gravity along the domed surface 36 toward the exterior of the chamber 35 and away from the axis 51.

The entire structure shown may be formed of various ceramic materials, the ball, however, being most satisfactorily of a hard glass.

It will be noted that no matter how much the device is shaken or joggled when in upright position, the bottle will not be open for refilling. It is not possible to insert any element through the opening 50 which will permit opening of the valve 22. It may be noted that there is no direct passage for the insertion of a pin or similar element from the opening 50 into the chamber 35 for moving the ball back toward the axis 51 of the structure, since the passageways 28 communicate with the space inside of the fins 44. It is necessary for the liquid flowing to the opening 50 from the chamber 35 to flow first to the side of the passages 42 before entering the passages 42 in passing across the main body 43 of the upper contact member 38.

The present construction is particularly advantageous inasmuch as it is possible to make the valve member 21 of a ceramic material. By permanently positioning the upper contact element 41 ceramically in the manner shown, the expanse of construction is materially decreased. The provision of four flow passages 28 past the valve casing 21, and three flow passages 42 past the upper contact member 38 assures a more even and better exit of liquid when the bottle is inverted for dispensing purposes.

The recesses 130, shown in Figs. 1 and 4, cooperate with the recesses 131 (see Fig. 1) in the bottom of the valve member 22, in the bottom of the casing member 13, and by means of these recesses suitable tools may be applied to the casing member 13 and to the valve member 22, whereby the seats 19 and 20 may be ground together to form a close formation. Preferably the corresponding valve face 20 and the valve seat 19 are preformed but during the process of firing the surfaces will become non-conforming and this grinding operation has been found most desirable.

These tool receiving recesses may take a variety of forms, other suitable recesses being the slots 130', indicated in Fig. 4a. The curvature of the lower ball contact element 30 is such that the ball will be retained in the locking position shown in Fig. 1 until the bottle is substantially completely inverted with the axis 51 coinciding with or being closely adjacent to a vertical position. When this angle is approached the ball will roll into the cavity 40 and the rate of pouring may then be controlled by inclining the inverted bottle away from the vertical position, the greater the inclination from said vertical position, the less the pouring rate. The curvature on the lower valve contact member 30 prevents jamming of the ball 31 and assures ready movement of the

ball from locking to unlocking position with proper positioning of the bottle.

The upper and lower casing members 12 and 13, the valve body 22, the valve cover 30, and the upper ball contact member 41 are all preferably formed of a white ceramic clay material, and in firing these materials, the upper ball contact element 41, and the upper outer casing 12 and the valve body 22 and its cover element 30 are fired in the position they take in the final device, shown in Fig. 1, so that they will be integrally and ceramically united into a unit. The outer surface of the casing 12 is preferably glazed, but the other surfaces are preferably unglazed.

In firing to permit the upper edge 133 of the casing 12 to be glazed, it is desirable that it be fired in upright position, as shown in Fig. 1, and to do so and at the same time maintain the upper ball contact element 41 in contact with the annular ribs 39, it is necessary that the lower casing element 13 be positioned inside of the upper casing 12 and act as a support for the upper casing during the firing operation. In this operation the upper ball contact element 41 will rest upon the inverted lower casing element 13 and the upper outer casing 12 in turn will rest upon said lower inverted casing 13 through said upper ball contact element 41.

In firing the valve element 22 with the cover in position the lower portion of the valve will be flattened due to the fact it is usually placed upon a table in upright position during such firing operation. After the lower ball contact element 30 has been substantially integrally united with the valve body 22 by the firing operation, the valve will be slightly porous. To prevent any air from escaping from the interior of the valve body, and also to prevent any liquid from entering the valve body maintaining its buoyancy, it is desirable to impregnate the valve body 22 after the firing operation with a suitable liquid wax or other water-proofing material, which will not be soluble or affected by any liquids which may be received in the bottle 10.

Referring to the upper valve contact element 41 the button 134 serves as a convenient means of centering the element 41 upon the ribs 39, and the ribs 45 in the cavity 40 prevent the ball from being adhesively connected to the cavity 40 when it is wet. The fact that the ball is not wedged, shown in Fig. 1, may be readily demonstrated by the fact that the ball can freely move around the peak of the lower contact element 30, without, however, permitting the valve 21 to be moved from its seat.

As indicating in Figs. 1 and 2 at 135, the exterior of the valve body 12 is preferably provided with a series of indentations or protrusions which enable the body to be conveniently gripped by a tool when the aluminum ferrule 16 is put into position.

What is claimed is:

1. In a non-refillable closure for liquid containing bottles and other containers, a main upper ceramic casing and a main lower ceramic casing of vitreous china forming a nipple portion of decreased diameter to be inserted into the top of the container, the upper casing being provided with a shoulder in a recess interiorly of the lower edge thereof to receive the lower casing, said recess being filled with a sealing means, not attacked by alcohol, and being also provided at its lower edge with an external flange connected in a liquid-tight fashion by a gasket and a metal-

lic ferrule to the top of a bottle, said casings each being provided with interior chambers, the lower chamber being provided with a center opening into the bottle and the upper chamber being provided with an outside pouring opening, the lower chamber receiving a hollow valve member, and the upper chamber receiving a ball lock in its lower part and an upper ball contact member, the valve member being provided at its upper face with a centrally peaked, laterally and concavely curved conical face cooperating with the ball lock and with an annular spherical-like valve face at its bottom cooperating with a correspondingly ground valve seat in said lower casing, said concavely-curved conical face serving to cause the ball to fall toward the exterior of said upper interior chamber when the closure is upright and the upper ball contact member being provided with a rib-faced central spherical concavity for receiving said ball when the closure is in inverted position, whereby said valve face may be removed from said valve seat by the force of gravity and the force of the liquid in the bottle, said valve being provided with a plurality of vertical centering fins and said upper casing being provided with a plurality of fins to permit free flow of liquid out through the closure when said closure is in inverted position.

2. In a non-refillable closure of material for liquid containing bottles and other containers, a ceramic casing provided with a nipple portion of decreased diameter to be inserted into the top of a bottle with an external flange to contact with the top of the bottle and limit the insertion of the cylindrical member, said casing being provided with two chambers, the lower chamber being provided with a center opening into the bottle and the upper chamber being provided with a pouring opening, the lower chamber receiving a hollow cylindrical-like valve member and the upper chamber receiving a ball lock and an upper ball contact member, the valve member being provided with a spherical face at its lower end cooperating with a spherical valve seat in the lower part of the lowermost chamber of said casing, the upper portion of said valve being provided with a curved centrally peaked surface for contact with the ball, causing said ball to roll toward the exterior of said upper chamber and the upper contact member being provided with a ribbed center concavity for receiving said ball when the bottle is in inverted position, whereby said valve member may be removed from said valve seat by the force of gravity and the force of the liquid in the bottle.

3. In a non-refillable bottle closure of the ball locking type, a ceramic casing with a nipple portion for insertion into a bottle, a reciprocable ceramic valve member and a ball therein, said valve member and said casing being provided with ball contact members, whereby said ball locks said valve in closed position when the bottle is in upright position and permits it to open when in inverted pouring position, said casing contact member and said casing being united by ceramic firing.

4. In a non-refillable closure of material for liquid containing bottles and other containers, a ceramic casing provided with a nipple portion of decreased diameter to be inserted into the top of a bottle with an external flange to contact with the top of the bottle and limit the insertion of the closure, said casing being provided with two chambers, the lower chamber being provided with a center opening into the bottle and the upper

chamber being provided with a pouring opening, the lower chamber receiving a hollow elongated valve member and the upper chamber receiving a ball lock and an upper ball contact member, the valve member being provided with an annular curved face at its lower end cooperating with a correspondingly shaped valve seat in the lower part of the lowermost chamber of said casing, the upper portion of said valve being provided with a centrally peaked surface for contact with the ball lock, causing said ball to roll toward the exterior of said upper chamber when the closure is upright, and the upper contact member being provided with a central concavity for receiving said ball lock when the closure is in inverted position, whereby said valve member may be removed from said valve seat by the force of gravity and the force of the liquid in the bottle, said valve member being of a ceramic material and being treated so as to be substantially non-porous and 20 said annular curved face and said valve seat being ground together.

5. In a non-refillable closure of material for liquid containing bottles and other containers, a ceramic casing provided with a nipple portion of decreased diameter to be inserted into the top of a bottle with an external flange to contact with the top of the bottle and limit the insertion of the closure, said casing being provided with two chambers, the lower chamber being provided with a center opening into the bottle and the upper chamber being provided with a pouring opening, the lower chamber receiving a hollow elongated valve member and the upper chamber receiving a ball lock and an upper ball contact member, the valve member being provided with an annular curved face at its lower end cooperating with a correspondingly shaped valve seat in the lower part of the lowermost chamber of said casing, the upper portion of said valve being provided with a centrally peaked surface for contact with the ball lock, causing said ball to roll toward the exterior of said upper chamber when the closure is upright, and the upper contact member being provided with a central concavity for receiving said ball lock when the closure is in inverted position, whereby said valve member may be removed from said valve seat by the force of gravity and the force of the liquid in the bottle, said peaked surface being concavely curved downwardly from the central peak, the curvature of which is approximately the curvature of the ball, whereby the ball may freely run around said center peaked portion while locking said valve member in position.

6. In a non-refillable closure of material for liquid containing bottles and other containers, a ceramic casing provided with a nipple portion of decreased diameter to be inserted into the top of a bottle with an external flange to contact with the top of the bottle and limit the insertion of the closure, said casing being provided with two chambers, the lower chamber being provided with a center opening into the bottle and the upper chamber being provided with a pouring opening, the lower chamber receiving a hollow elongated valve member and the upper chamber receiving a ball lock and an upper ball contact member, the valve member being provided with an annular curved face at its lower end cooperating with a correspondingly shaped valve seat in the lower part of the lowermost chamber of said casing, the upper portion of said valve being provided with a centrally peaked surface for contact with the ball lock, causing said ball to roll toward the

exterior of said upper chamber when the closure is upright, and the upper contact member being provided with a central concavity for receiving said ball lock when the closure is in inverted position, whereby said valve member may be removed from said valve seat by the force of gravity and the force of the liquid in the bottle, the rim at

the top of said bottle and the contacting flange on said closure being separated by a compressible gasket and a metallic ferrule encircling said flange and pressing them tightly together and compressing said gasket.

GILBERT JACKSON.
